UNITED STATES PATENT OFFICE.

MICHAEL E. NEENAN, OF NEW YORK, N. Y., ASSIGNOR TO OTIS ELEVATOR COMPANY, OF JERSEY CITY, NEW JERSEY, A CORPORATION OF NEW JERSEY.

ELEVATOR.

988,016.

Specification of Letters Patent. Patented Mar. 28, 1911.

Application filed April 1, 1907. Serial No. 365,704.

To all whom it may concern:

Be it known that I, MICHAEL E. NEENAN, a citizen of the United States, residing at New York, in the county of New York and State of New York, have invented a new and useful Improvement in Elevators, of which the following is a specification.

My invention relates to frictional driving apparatus for elevators, similar to that disclosed in my Patent No. 912,256, February 9, 1909, for improvement in elevators.

The principal object of my invention is the provision of a tensioning device in a traction elevator system to render the latter more efficient by reducing the slipping of the power-transmitting means to a minimum.

Other objects of my invention will appear hereinafter, the novel combinations of elements being pointed out in the appended claims.

In the accompanying drawings, Figure 1 represents more or less diagrammatically a traction elevator system embodying my invention; Fig. 2 is a similar view showing a modification; Figs. 1^a, 1^b, 1^c and 1^d are detail views of slightly modified forms of the equalizing device itself; Figs. 3, 3^a, 4, 5 and 7 are diagrammatic elevations of still further modifications which illustrate modes of carrying into effect the principles of my invention; Fig. 6 represents in elevation another modification; Fig. 8 is an elevation of the car and its appurtenances showing an additional modification; Fig. 9 is a bottom view of the car and its accessories shown in Fig. 8; and Figs. 10 and 11 are detail views.

The power-transmitting means in this instance comprises ropes or cables passing on and off the driving apparatus and associated with these ropes or cables, is a device whereby the tension throughout said cables is regulated by the load suspended directly by said cables or a connection therefrom. By this arrangement embodying my invention, weights as used heretofore to apply tension to the cables may be dispensed with or used if desired in addition and it is rendered impossible for any increased load upon the car or sudden stoppage of the same, or sudden starting of the driving apparatus, to cause the latter to slip. To this end the ropes and sheaves are so disposed, and the car so suspended therefrom, that while the weight of the car, or of the car and its load holds in

tension its direct suspension and hoisting ropes, it also holds in tension the opposite leads of the ropes and takes up the slack thereof, and applies greater tension to the said opposite leads of the ropes when the load on the car causes increased tension on its direct suspension or hoisting ropes, and vice versa.

Referring to Fig. 1, 11 designates an elevator car suspended at one end of the car ropes 12 which extend over a sheave 33 and are attached at their other ends to the counterweight 36. The sheave 33 is hung to the ends of the driving rope or cable 40, as for example, by means of the yoke 18^a. 60 This driving rope or power-transmitting means passes over the fixed sheave 13, that is, over the sheave 13 having a fixed pivot or bearing mounted for instance on the fixed beam 45. Thence the driving rope 40 extends downwardly under a sheave 41 mounted on the upper side or on the top of the counterweight 36; thence up and over a lever 42, having a fixed pivot or bearing mounted on the fixed beam 46; thence downwardly to the yoke 18^a to which it is connected. The other end of the rope 40 is also connected to the yoke 18^a and extends upwardly over the lever 42 in an additional groove therein, and then extends down and around the fixed sheave 44, up to and around the sheave 43 mounted on the bottom of the counterweight 36, and finally down and around the motor-drum or motor sheave 14 of the driving apparatus. Or, starting with 65 one end of the rope 40, it may be traced in succession around the lever 42, sheaves 41, 13, 14, 43, 44 and lever 42 back to the yoke or hanger 18^a. Under this arrangement the car is moved up or down by the movement 70 imparted to the counterweight 36 by the driving rope 40 which is drawn in either direction by the motor-drum or motor sheave 14. The weight of the car applied to the driving rope 40 through the equalizing device 42 maintains tension on said driving rope, automatically takes up any slack therein, and regulates the friction of the motor-drum 14 according to the load on the car. 75

Now it is evident that when the car is 80 being lifted or lowered the bearing of sheave 33 will remain substantially stationary except upon changes of load due either to actual changes therein or to inertia. For instance, if the car is to be lifted, the inertia 85

of starting must be overcome and there will be a tendency of the driving sheave 14 to slip on the driving rope 40. To lift the car the sheave 14 must be rotated in an anti-clockwise direction as viewed in Fig. 1. There will then be a tendency for the right-hand lead of the driving rope winding off the drum to become slack, but this tendency is counteracted by the downward pull on the counter-weight and the consequent downward pull on the sheave 33, which pull is transmitted along that portion of the rope 40 passing under the sheave 41 and over the sheave 13. The tendency for the right-hand lead to be come slack being thus overcome, slipping of the driving sheave 14 on the rope 40 will be prevented. It is evident that when the inertia of the car is thus to be overcome in starting, and the counterweight 36 is moved slightly downwardly before the car is actually started, the consequent slight downward movement of the sheave 33 will produce a tilting or oscillating movement of the lever 42.

After the car is under way the sheave 43 rolls onto that portion of the rope 40 between said sheave 43 and the sheave 44. At the same time the sheave 41 lengthens the loop in which it rotates. The anti-clockwise rotation of the driving sheave 14 takes up that portion of the cable 40 passing downwardly from the sheave 43 to the sheave 14, and pays out that portion of the rope 40 passing downwardly from the sheave 13 to the sheave 41. It will thus be obvious that the oscillating movement of the equalizing device 42 is very limited, and that there is substantially no movement thereof except upon changes of load that the motor 40 must drive. Obviously a sheave 42', as shown in Fig. 2, may be substituted for the lever 42 if desired. It is advantageous to maintain the portions of the rope extending downwardly in a vertical position, but this may be accomplished either by a lever 42, as shown in Fig. 1, with arc-shaped end portions, or by a sheave 42' as in Fig. 2. Figs. 1^a, 1^b, 1^c, and 1^d show various modifications of the equalizing device 42. In Fig. 1^a is shown a lever 42^a which in reality is a sheave with portions cut away therefrom, the grooves 45 and 45' being shown out of lateral alinement for the sake of simplicity in illustrating the rope connections. In this instance the ropes 40 pass horizontally across the top of the lever 42^a and thence downwardly on the left hand side as viewed in Fig. 1^a to the yoke 18^a. If desired the ends of the rope 40 may be fastened to the right-hand portion of the lever 42^b as indicated in Fig. 1^b, and then additional ropes 40', 40' fastened to the left-hand portion thereof and placed in the grooves 45, 45'. In Fig. 1^c the lever is still further modified so that the end grooves are not arc-shaped, but vertical.

The lever 42^c then appears as a simple straight lever having two grooves for receiving the end portions of the rope 40. As in Fig. 1^b, I have illustrated how the rope 40 may be fastened to the lever 42^b, so also in Fig. 1^d I have shown the upper ends of the rope 40 secured to the right-hand end of the lever 42^d. The left-hand end of the lever 42^d is then connected by short sections of rope 40', 40' to the yoke 18^a. Whether the pulley 42' or one of the forms of simple levers illustrated in Figs. 1, 1^a, 1^b, 1^c and 1^d be used, the operation of the invention is substantially the same. Furthermore it is obvious that various changes in the details of such a tensioning device may be made by those skilled in the art and still fall within the principles of my invention, and I desire, therefore, not to be limited to any particular form of such tensioning device. Although in Fig. 1 I have shown a motion-reduction gear of two-to-one, referring to the reduction of motion between the rope on the face of the driving drum and that attached to the car, by modifications this can be carried out to any extent desired in connection with the tensioning device.

As shown in Fig. 2, the sheave 33 may be suitably suspended wholly from the upper section of the driving rope 40, the lower section thereof being attached at a fixed point, for instance, that designated 44^a, instead of passing around a fixed lever or sheave, that is, a lever or sheave having a fixed pivot or bearing. With such an arrangement it is evident that the sheave 42' acts as an equalizing or take-up device, for upon any downward movement bodily of the sheave 33, the device 42' will be slightly rotated, tilted or oscillated to take up the slack in the lead winding on the drum 14, or the lead winding off the drum 14. The device 42' may be substituted by one of the levers illustrated in Figs. 1^a, 1^b, 1^c and 1^d, and the operation would be the same. For instance, if the sheave 14 is rotating in a clockwise direction and the car 11 therefore traveling downwardly, and the motor M is slowed down and stopped by effecting the application of a brake thereto, in any well known manner, there will be a tendency for the rope 40 to slip on the sheave 14, due to the inertia of the car. The upward pull on the hoisting rope 12 tends to continue to lift the counter-weight 36 and produces a strong pull on the left-hand lead of the driving rope against the fixed point 44^a, and such upward movement of the counterweight 36 tends to slacken the right-hand lead adjacent the motor-drum 14. This tendency to slacken, however, is overcome by the slight rotation or movement to a limited degree of the equalizing device 42' in an anti-clockwise direction, thus tightening the right-hand lead. The downward bodily movement of the sheave 33 to pro-

duce a slight tilting or rotative movement of the sheave 42' is due to the inertia pull of the car against the counterweight which is held substantially stationary by the lower section of the rope 40 at the fixed point 44^a and at the motor sheave 14 which has been stopped. It is now evident that by adding additional weight to the car when the driving drum 14 and the counterweight 36 are thus held stationary, both portions of the driving rope 40 leading to or from the sheave 14, are tightened in proportion to such addition to the load.

Although the motor may be of any type, as for instance, steam, hydraulic, alternating current, direct current, etc., it is preferable to employ an electric motor directly connected to the driving sheave 14. Any suitable controlling means may be employed in connection with such motor, that shown in Fig. 1 being merely by way of illustration. As there indicated, an electric reversing switch 47 is connected between the positive and negative mains and the motor terminals, and this reversing switch is operated by the electro-magnetic mechanism 48 controlled from the car by the manual electric switch 49.

In the modification shown in the diagram, Fig. 3, a loose sheave 29 is suspended from the upper ends of the driving ropes 40, which in this instance are also the suspension ropes. The other ends of these ropes are connected to the top of the car 11 and extend upwardly over the suspended sheave 29 and thence downwardly along one side of the car and around the guide sheaves 15^a and 15 mounted on the bottom of the car. Thence the ropes pass downwardly to the driving sheave 14 which is connected to the electric motor M. In this instance the equalizing or take-up sheave 29 and the guide-sheaves 15^a and 15 move up and down with the car. In this illustration of the invention the downward strain on the car applied to the terminal ends of the suspension and driving ropes 40, will, through the medium of the loose sheave 29, apply double tension to the upper sections of said ropes and single tension to the lower sections so as to increase or decrease the said tensions on the ropes corresponding with the load on the car. If desired, the take-up device 29 may be replaced by a simple straight lever 29^a pivoted to the top of the car at 50, as illustrated in Fig. 3^a. The operation will then be substantially the same except that the tensions in the leads may be varied with respect to each other by varying the point of connection of the rope 40 with the lever 29^a.

Fig. 4 is similar to Fig. 3 but shows the invention applied to the well known differential speed drum elevator mechanism. 12 designates the main hoisting rope connected

sheave or take-up device 29^b, and passing over the sheave 13 having a fixed pivot. The loose sheave 29^b is, therefore, suspended from the upper section of the rope 12. 12^a is a separate rope section passing over the loose sheave 29^b and connecting the car with the loose sheave 35. 14^a and 14^b designate differentially rotated driving drums, and 40 the endless rope driven thereby and carried over the loose sheaves 34 and 35, hung from the right-hand extremities, as viewed in Fig. 4, of the ropes 12 and 12^a, respectively. In this illustration likewise, the strain applied to the rope 12 by the weight of the car and its load through the medium of the take-up sheave 29^b, will counteract or take up the slack and automatically graduate the tension on the opposite leads of the ropes to correspond with the load, as before explained.

The same effect described with reference to Fig. 3 may be produced with the arrangement of ropes shown in Fig. 5, in which the bottom sections of the ropes are carried around the guide sheaves 15, 15^a, 15^b, 15^c, and thence over the loose sheave or take-up device 29^c, and attached to the top of the car. This produces a double take-up effect by extending the ropes around the sheaves 15^c and 29^c.

Substantially the same effect as produced by the arrangement illustrated in Fig. 5 may be obtained by the arrangement shown in Fig. 7. Here the driving rope 40 extends upwardly from the driving sheave, as in Fig. 3, and thence around the guide sheave 15 on the bottom of the car, around the guide sheave 15^d also on the bottom of the car, and thence around the take-up sheave 29^e to the fixed point 5'. The other portion of the rope 40 extends upwardly around the sheave 13 having a fixed pivot, thence downwardly around the guide sheaves 15^c, 15^b, and 15^a to the sheave 29^e to which it is connected. It will, therefore, be seen that the sheave 29^e has substantially the same effect as the sheave 29 in Fig. 3, the lever 29^a in Fig. 3^a, the sheave 29^b in Fig. 4, and the sheave 29^c in Fig. 5. In fact the sheave 29^e may be replaced by a lever if desired in the same manner that Fig. 3 is shown modified in Fig. 3^a.

In the modification shown in Fig. 6 the car ropes 40 are carried around the guide sheaves 15^c and 15^b, and are connected at their ends to levers 29^d fulcrumed at 30 on the bottom of the car. The connections of the car suspension ropes with the levers 29^d are near the fulcrums thereof, and the meeting ends of said levers are connected to the lower section of the ropes extending up from the driving drums 14, 14. In Fig. 6 I have illustrated the motor shaft at 52 which is connected to a friction device engaging the peripheries of the disks or wheels 53 and 54, the latter being connected with

the drums 14, 14, to cause the said drums to rotate with said disks. With this arrangement the right-hand lead of the driving rope extends downwardly under the 5 lower drum 14, thence upwardly over the upper drum, downwardly under the lower drum 14 again, and finally upwardly past the guiding sheave 55 to the bottom of the car. The meeting ends of the levers 29^a 10 are also connected to the depending end of the rope 31 running over the fixed sheave 15^a on the bottom of the car, and attached to the end of the rope counterbalance chain 32 which is suspended therefrom. This 15 chain serves the double purpose of counter-balancing the weight of the lower parts of the ropes 40 exerted on the tension device from which they are suspended at the bottom of the car, as this lower part of the 20 ropes is elongated as the car rises; and also in conjunction with said ropes, counter-balancing the weight of the suspension ropes above the car as this is elongated when the car descends. In practice the weights of 25 the ropes and chain are properly proportioned to effect a substantially perfect rope counterbalance. In this illustration, (Fig. 6), the weight of the car tending to lift the levers 29^a, will apply tension to the lower or 30 opposite lead of the ropes 40, graduated according to the lever proportions, so that—as in the other illustrations—the tension on all the ropes extending on both sides of the driving drums is regulated by the load on 35 the car; increased load producing greater tension, and less load less tension.

In the modification shown in Figs. 8 and 9, the lower ends of the suspension ropes 40, after passing around the guide sheave 15 40 on the bottom of the car, are carried around a second guide sheave 15^a and coiled on a take-up sheave to which their ends are secured. Integral with or fixed to the sheave 29^a so as to turn therewith, is a smaller 45 sheave 28 on which the upper parts of the rope 40 are coiled so that a strain applied to the said ropes by the load on the car tends to rotate the combined sheaves 29^a, 28, and thereby wind up the lower part or section of 50 the ropes 40 on the larger sheave 29^a, thus, as before, taking up the slack and applying tension to the lower or opposite lead of the ropes regulated by the load on the car. Here also it is evident that the same result 55 may be produced by replacing the horizontally disposed sheaves on the bottom of the car by levers of sufficient length to secure the desired result.

While each of the arrangements described 60 possesses structural and operative advantages of its own, and some of the parts thereof are interchangeable, it will be evident that the different arrangements of the sheaves or levers of the tension device afford

simple means for causing the weight of the 65 car to graduate the tension to be applied to the ropes or cables on both sides of the driving drum or sheave, and consequently friction between the same. The single movable sheave 29^a, as in Fig. 7, produces the tension 70 of two-to-one. The levers 29^a shown in Fig. 6 and the two sheaves 28, 29^b shown under the car in Fig. 8, which sheaves act virtually as continuous levers, admit of a finer graduation and can be used to obtain this effect, if 75 found desirable, in the other structures.

Heretofore, in frictional driving elevator mechanism, the weight of the tension devices was fixed according to the maximum load the elevator was built to carry. Hence it 80 will be clearly apparent that the weight of the tension device above that required by the various loads is detrimental, causing loss of power and increased wear on the mechanism, and consequent reduction in the life of the 85 same; whereas, my invention achieves the ideal result in frictional driving elevator machinery in causing the tension on the ropes on both sides of the driving drums to increase or decrease automatically according 90 to the load.

In the foregoing description I have referred to "ropes or cables" in the plural number, and have shown a plurality of ropes in Figs. 10 and 11, for the reason that in 95 hoisting systems the hoisting ropes are used in gangs or in multiple for additional security; although a single rope may be used except where the ropes are bifurcated or separated to pass around opposite sides of 100 the car. The invention may, of course, be used with one or any desirable number of ropes.

Obviously those skilled in the art may make various changes in the details and arrangement of parts without departing from the spirit and scope of my invention, and I desire, therefore, not to be limited to the precise construction herein disclosed.

Having thus described my invention, what 110 I claim and desire to have protected by Letters Patent of the United States is:—

1. In a frictional driving mechanism, the combination with frictional driving apparatus, of a load-carrying device, connecting 115 means between said frictional driving apparatus and said load-carrying device, and a single device associated with said connecting means to effect a variation of tension in the latter when the load varies.

2. The combination of a frictional rope driving apparatus, flexible power-transmitting means driven thereby, a load-carrying device, and a single rotatable take-up device 125 for changing the tension of the leads winding on and off the driving apparatus in proportion to changes of load.

3. In an elevator, the combination with

- frictional driving apparatus, of a load-carrying device, flexible ropes or cables connecting said load-carrying device with the driving apparatus, and a single equalizing device having a limited degree of movement and being associated with said cables to tighten the leads extending from said driving apparatus when the load varies.
4. In an elevator, the combination with 10 frictional rope driving apparatus, of a load-carrying device, power-transmitting means comprising flexible ropes or cables, and a single tensioning device for tightening the leads on said rope driving apparatus upon 15 changes of load.
5. In a frictional driving elevator, the combination with frictional driving apparatus, of a load-carrying device, flexible power-transmitting means connecting the 20 driving apparatus and the load-carrying device, and a member movable on a fixed pivot or bearing for regulating the tension in said flexible means to effect a variation of tension in the latter in proportion to variations of 25 load.
6. The combination with driving apparatus, of a load-carrying device, power-transmitting means connecting the driving apparatus and said load-carrying device, and a device mounted on a fixed bearing or pivot 30 and associated with said power-transmitting means to change the tension in the latter when the load changes.
7. The combination with a driving sheave, 35 of a load-carrying device, flexible connections between the sheave and the load-carrying device, and a movable member mounted on a fixed support and associated with said connections to cause the load to maintain 40 sufficient tension in said connections.
8. The combination with driving apparatus, of a load-carrying device, power-transmitting means connecting the driving apparatus and said load-carrying device, and an oscillating device supporting the load to 45 effect tension in the power-transmitting means.
9. The combination with a driving drum or sheave, of a load-carrying device, power- 50 transmitting means connecting the drum and load-carrying device, and a single device having a limited degree of movement to cause the load to place said power-transmitting means under tension and to vary 55 such tension upon variations of load.
10. The combination with a driving sheave, of a carrier, a rope system connecting the carrier and the driving sheave, and a tilting lever supporting the carrier and 60 load to cause the rope system to be placed under tension.
11. The combination with a driving sheave, of a load-carrying device, a rope system connecting the driving sheave and 65 load-carrying device, and a tilting lever supporting the load-carrying device to effect variable tension on the rope system.
12. The combination with a driving sheave, of a movable member, a rope or ropes connecting the movable member and the driving sheave, and a leverage system operated by said member to effect the maintenance of frictional engagement between the rope or ropes and the driving sheave.
13. The combination with a driving 75 sheave, of a rope or ropes in frictional engagement with said driving sheave, a load-carrying device connected to said rope or ropes, and a tilting lever supporting the load-carrying device to increase the tension 80 on said rope or ropes in the leads winding on and off the driving sheave.
14. The combination with a driving sheave, of a load-carrying device, a rope or ropes in engagement with said sheave and 85 connected to said load-carrying device, and a tilting lever supporting the load-carrying device to increase the tension on said rope or ropes on both leads extending from the driving sheave in proportion to the load.
15. The combination with a driving sheave, of an elevator car, a rope system associated with said driving sheave and connected to the car, and a tilting lever supporting the car to cause the same to place 95 the rope system in tension.
16. The combination with a driving sheave, of an elevator car, a rope or ropes connecting the car and the driving sheave, and a leverage system actuated by the car 100 to effect the maintenance of frictional engagement between the rope or ropes and the driving sheave.
17. The combination with driving apparatus, of flexible power-transmitting means, 105 an elevator car, and a tilting lever supporting the car to increase the tension in both the leads of the power-transmitting means running on and off the driving apparatus.
18. In a rope drive elevator, the combination with a car, of driving apparatus, a rope system associated with said driving apparatus, and a tilting lever supporting the car and associated with said rope system to control the frictional contact between the parts of the driving sheave and the rope system in engagement with each other.
19. In a frictional driving elevator, the combination with driving apparatus, of an 115 elevator car, ropes connecting the driving apparatus and car, and a single movable member associated with said ropes to effect the application of tension in the latter in proportion to the load.
20. The combination with a frictional driving apparatus, of a load-carrying device, flexible power-transmitting means for 120 125

connecting the load-carrying device to the driving apparatus, and a single movable member for effecting a variation in the tension of all the leads of said connecting means in direct proportion to variations of load.

21. The combination with a frictional driving apparatus, of flexible power-transmitting means driven thereby, a load-carrying device connected to said means, and a device having a fixed bearing or pivot and associated with said power-transmitting means to change the tension in the opposite leads winding respectively on and off the driving apparatus when the load changes.

22. The combination of a frictional driving apparatus, flexible power-transmitting means driven thereby, a load-carrying device, and a single oscillating device associated with said power-transmitting means to effect a change in tension with a change of load in the leads winding respectively on and off the driving apparatus.

23. The combination with a frictional driving apparatus, of a load-carrying device, flexible ropes or cables connecting said load-carrying device to the driving apparatus, and a member mounted on a fixed support and associated with said ropes or cables to effect a variation in tension in the leads of said ropes winding on and off the driving apparatus, said tension being in a predetermined ratio to the weight of the load.

35 24. In an elevator, the combination with frictional driving apparatus, of a load-carrying device, flexible ropes or cables connecting said load-carrying device to the driving apparatus, and a pivoted device associated with said cables for automatically effecting a variation in the tension of the leads winding on and off the driving apparatus in a predetermined direct ratio to the variation of load.

45 25. The combination of a frictional driving apparatus, ropes driven thereby, a load-carrying device connected to said ropes, and a give-and-take connection comprising a fixed bearing and associated with said ropes to effect an upward pull thereon to tighten the same on the driving apparatus when the load varies.

55 26. In a friction driving elevator mechanism, the combination of a load-carrying device, frictional driving apparatus, flexible power-transmitting means looped around the driving apparatus and driven thereby, and a single device associated with said power-transmitting means to effect an upward pull thereon whereby the weight of the car and its load holds tight all the leads winding respectively on and off the driving apparatus, and the tension on said leads changes with the load.

65 27. In a frictional driving elevator mecha-

nism, the combination of a car, a frictional driving drum, a rope take-up device operated by the car and its load and located near one of the limits of travel of the car, and ropes connecting the car and driving drum 70 and associated with said take-up device.

28. In a friction driving elevator mechanism, the combination of a car, a frictional driving drum, power-transmitting ropes looped around the drum, and connected by 75 their on-winding and off-winding leads to car-suspending means, and a rope take-up device mounted near the upper limit of travel of the car, associated with said power-transmitting ropes and co-acting with the 80 car suspension means to permit variations of load to vary the tension in the leads extending from the driving drum.

29. In a friction driving elevator mechanism, the combination of a car, a hoisting 85 rope or ropes therefor, a driving device in frictional engagement with said ropes, and a rope take-up device comprising a lever actuated by the weight of the car and its load to apply tension to the leads of the ropes 90 winding on and off the driving apparatus, such tension changing with the load.

30. In a friction driving elevator mechanism, the combination of a car, a frictional driving drum, ropes driven by said drum, 95 a weight associated with said ropes, a tension lever device connected to said ropes and operated by the car and weight, and suitable suspensory connections between said car and weight and said tension device.

31. In a frictional driving elevator mechanism, the combination with an elevator car, of a driving drum, driving ropes associated with said drum, a tension slack rope take-up device mounted at or near the upper end of 105 the elevator well, and suspensory connections between the ropes and take-up device and the car, said take-up device operating to apply variable tension and pressure to the ropes and frictional driving mechanism, respectively, governed by the load on the car.

32. In a frictional driving elevator mechanism, the combination with an elevator car, of a frictional driving drum, driving ropes in frictional engagement with said driving drum, and slack rope take-up means mounted at the upper end of the elevator well and effecting the application of tension in the driving ropes on both sides of the driving drum automatically variable in unison with 115 variations in the load on the car.

33. A driving sheave, an elevator car arranged to be moved thereby, a rope system connecting the car and the driving sheave, and a tilting lever arranged to support the elevator-car and to cause the weight of the car to make tension on the rope system.

34. A driving sheave, an elevator-car, a rope or ropes connecting the car and the driving sheave, and a leverage system actu-

- ated by the effective weight of the car and arranged to keep the rope or ropes in frictional contact with the driving sheave.
35. A driving sheave, a rope or ropes passing around and by two sides of said sheave, a movable member connected to said rope and a tilting lever arranged to support the movable member and to increase the tension on said rope or ropes on both sides of the driving sheave. 70
36. A driving sheave, a rope or ropes passing around and by two sides of said sheave, a receptacle adapted to carry a load connected to said rope or ropes, and a tilting lever arranged to support the receptacle and to increase the tension on said rope or ropes on both sides of the driving sheave in proportion to the weight of the receptacle and its load. 75
- 20 37. The combination with frictional driving apparatus, of a load carrying device, connecting means between the frictional driving apparatus and said load carrying device, and a lever for regulating the tension 25 of said connecting means to effect a variation of tension throughout the latter in proportion to variations of load. 80
38. In frictional driving apparatus, the combination with a load carrying device, of driving apparatus, power transmission means, and a movable lever actuated by the load carrying device to hold said power transmission means in tension throughout according to the load. 85
- 35 39. In a frictional driving elevator, the combination with driving apparatus, of a load carrying device, flexible driving means in frictional driving connection with said driving apparatus and extending therefrom 40 in opposite leads, and a take up or tension lever connected to said leads and to the load carrying device to change the tension on said leads according to the load. 90
40. In a frictional driving elevator, the combination with driving apparatus, of a load carrying device, flexible driving means in frictional driving connection with said driving apparatus and extending therefrom in opposite leads, and a take up or tension lever connected to said leads and to the load carrying device to change the tension on said leads according to the load. 95
41. In a frictional driving elevator, the combination with frictional driving apparatus, of a load carrying device, flexible means for connecting the driving apparatus to said load carrying device, and a pivoted tension lever for regulating the tension of said flexible means to effect a variation of tension throughout the latter in proportion to variations of load. 100
42. In a frictional driving elevator, the combination with driving apparatus comprising a rope, of an elevator car, a flexible connection between the driving apparatus 105 and the car, and a pivoted tension lever connected to said rope and operated by variations of load to change the tension of all the leads winding respectively on and off the driving apparatus. 110
43. The combination with frictional driving apparatus comprising power transmitting ropes, of a load carrying device, and means comprising a pivoted tension lever for effecting a variation in the tension of all the leads of the driving apparatus in a predetermined ratio to the weight of the load. 115
44. The combination with a frictional driving apparatus, of a load carrying device, power transmission means, connecting means through which the said load carrying device places said power transmission means in tension throughout according to the load, and a tension holding device, comprising a lever. 120
45. The combination with a friction drive member, of a load-carrying device, power transmission means, and a pivoted lever actuated by the load carrying device to hold said power transmission means in tension throughout according to the load. 125
46. The combination with a friction drive element, of a load carrying device, flexible power transmitting means, and a lever connected to said means and to said load-carrying device to effect changes in the tension in said flexible means throughout corresponding to variations in the load. 130
47. The combination of frictional driving apparatus a load-carrying device, connecting means between the frictional driving apparatus and the load-carrying device, and a pivoted member for regulating the tension of said connecting means to effect a variation of tension throughout the latter corresponding to variations of load, the pivot for said member being substantially stationary during the normal travel of the load-carrying device. 135
48. In frictional driving apparatus, the combination of a load carrying device, driving apparatus, power transmission means, and means having a substantially stationary location during the travel of the load carrying device and actuated by the latter to hold said power transmission means in tension throughout according to the load. 140
49. A driving sheave, a frame arranged to be moved thereby, a rope system connecting the movable frame and the driving sheave, a receptacle adapted to carry a load associated with the movable frame and arranged to be moved thereby, and a tilting lever arranged to support the receptacle and to cause the receptacle to make tension on the rope system. 145
50. A driving sheave, a frame arranged to be moved thereby, a rope system connecting the movable frame and the driving sheave, a receptacle adapted to carry a load asso- 150

ciated with the movable frame and arranged to be moved thereby, and a leverage system arranged to cause the weight of the receptacle and its load to make tension on the rope system.

51. A driving sheave, a frame arranged to be moved thereby, a weight connected to the frame, a rope system connecting the movable frame and the driving sheave, a receptacle 10 adapted to carry a load associated with the movable frame and arranged to be moved thereby, and a tilting lever arranged to support said receptacle and to cause the weight of the receptacle and load to make tension 15 on the rope system.

52. A driving sheave, a frame arranged to be moved thereby, a rope system connecting the movable frame and the driving sheave, a receptacle adapted to carry a variable load 20 associated with the movable frame and arranged to be moved thereby, and a tilting lever arranged to support the receptacle and to cause the weight of the receptacle and its variable load to produce a variable tension 25 on the rope system.

53. A driving sheave, a rope or ropes passing around and by two sides of said sheave, a movable frame carried by said rope or ropes, a receptacle adapted to carry a load 30 associated with said frame and arranged to be moved thereby, and a tilting lever ar-

ranged to support the receptacle to increase the tension on said rope or ropes on both sides of the driving sheave in proportion to the weight of the receptacle and its load. 35

54. A driving sheave, a car arranged to be driven thereby, a rope system connecting the car and the driving sheave, said rope system being arranged to cause the car to be driven at a different rate of speed from that of the 40 driving sheave, and a tilting lever arranged to support the load and to produce an equalized tension on the rope system.

55. A driving sheave, a driving rope associated therewith, a car adapted to carry a 45 load arranged to be driven by said driving rope, a rope system connecting the load and the driving rope, said rope system being arranged to cause the rope to be driven at a different rate of speed from that of the driving rope, and a leverage system arranged to cause the weight of the car and its load to produce an equalized tension on all parts of the driving rope in proportion to the weight 50 of the car and its load. 55

In testimony whereof, I have signed my name to this specification in the presence of two subscribing witnesses.

MICHAEL E. NEENAN.
